UNITED STATES PATENT OFFICE.

WILLIAM M. WOOD, OF PHILADELPHIA, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

GAS-GOVERNOR.

1,206,282.

Specification of Letters Patent. Patented Nov. 28, 1916.

Application filed November 27, 1915. Serial No. 63,866.

To all whom it may concern:

Be it known that I, WILLIAM MUSGRAVE WOOD, a citizen of the United States, and a resident of Philadelphia, in the county of Philadelphia and State of Pennsylvania, have invented certain new and useful Improvements in Gas-Governors, of which the following is a specification.

A gas pressure regulator or governor is dependent for its operation upon a flexible diaphragm carrying a centrally disposed weight which is supported by the gas pressure. The pressure regulation is not uniform for various rates of gas flow because the effective pressure area of the diaphragm changes with the various positions of the centrally disposed weight due to the flexible annular portion of the diaphragm between the rim of the weight and the support for the edge of the diaphragm.

The principal object of the present invention is to increase the uniformity of regulation of such governors and to this end, stated generally, the invention comprises the provision, or combination with such governors, of mechanism for automatically loading and unloading the diaphragm in accordance with the changing increments of effective area.

The invention will be claimed at the end hereof, but will be first described in connection with the embodiment of it chosen for illustration in the accompanying drawings in which—

Figure 1, is a longitudinal sectional view of a gas governor provided with mechanism embodying features of the invention. Fig. 2, is a transverse sectional view of the same. Fig. 3, is a diagrammatic view illustrating the changing effective area of the diaphragm. Fig. 4, is a longitudinal sectional view illustrating a modification of the invention, and Fig. 5, is a diagram to which reference will be hereinafter made.

When the weight 1, and the diaphragm are, for example, in the position shown by full lines in Fig. 3, the effective area of the diaphragm is measured by the diameter indicated by the arrow 2, but when the weight and diaphragm are in the position indicated by dotted lines, the diameter of its effective area is indicated by the arrow 3, which is evidently much greater than the diameter 2, and in intermediate positions there are corresponding changes in the effective area of the diaphragm. This means that as the

rate of flow of gas is increased at the house connection 4 of the governor the pressure of the gas is decreased more than with the reverse of this action when the rate of flow of gas is diminished. This is due to the above described changing effective area of the diaphragm as the same changes its position. In Fig. 5, the line *a*—*b*, indicates the pressure due to the described operation of the diaphragm. This diaphragm operates the valve 5, which is connected to the short end of a lever 7, pivoted at 8, and connected with a stem 9, of the diaphragm.

By my invention weight is added to and subtracted from the diaphragm and its connected parts as indicated by the dotted line *c*—*d*, in Fig. 5. This dotted line *c*—*d*, in Fig. 5, shows the pressure equivalent of this added weight as compared with the line *a*—*b*. The result of the added weight is to produce a substantially uniform pressure *a*—*e*, at the outlet 4, for all positions of the diaphragm and its weight within the capacity of the governor.

As shown in Figs. 1 and 2, 10, is a weight pivoted at 11, and shown as consisting of two lobes straddling the spindle 9, and each of about the shape in cross-section of the third of a circle. By means of links 12, this weight is connected with the spindle 9.

As the invention is not limited to a weight, I have illustrated its equivalent in the spring 13, Fig. 4, connected with the arm 14, of the bell-crank pivoted at 15, and having its other end 16, connected by slot-and-pin connection with the spindle 9. As the diaphragm descends, the weight 10, is turned counterclockwise in Fig. 1, its effect upon the diaphragm constantly increasing, with a reverse action when the weight is turned clockwise by the diaphragm being raised. The effect of the spring 13, Fig. 4, also increases as the arm 14, is turned counterclockwise by the diaphragm descending with the reverse effect when the arm 14, is turned clockwise. The dotted line *c*—*d*, Fig. 5, illustrates this change of effect of the spring or the weight upon the diaphragm and this changing effect offsets or neutralizes the effect due to the changing effective area of the diaphragm, so that the pressure at the outlet 4, is substantially constant within the capacity of the governor.

What I claim is:

1. In a gas governor the combination of

a rim supported flexible diaphragm and its valve connection, a weight applied to the diaphragm to balance the gas pressure, and means for automatically loading and unloading the diaphragm to compensate for variations in the effective area thereof and to produce a uniform gas pressure, substantially as described.

2. In a gas governor the combination of 10 a rim supported flexible diaphragm and its valve connection, a weight applied to the diaphragm to balance the gas pressure, a pivotal weight for automatically loading and unloading the diaphragm to compensate for variations in the effective area thereof, and means for supporting the pivotal weight in unstable equilibrium, substantially as described.
3. In a gas governor the combination of 20 a rim supported flexible diaphragm and its

valve connections, a weight applied to the diaphragm to balance the gas pressure, and a pivotal weight for automatically loading and unloading the diaphragm to compensate for variations in the effective area thereof, substantially as described.

4. In a gas governor the combination of a weighted rim-supported flexible diaphragm, a spindle and valve connections for the diaphragm, a pivotal weight overhanging its support and provided with lobes straddling the spindle, and links interposed between the weight and spindle, substantially as described.

In testimony whereof I have hereunto signed my name.

WILLIAM M. WOOD.
